CLAIM

The ornamental design for a seat, as shown and described.

DESCRIPTION

FIG. 1 is an isometric view of the seat of my new design having two seating sections;

FIG. 2 is a left side elevational view thereof, the right side elevational view being a mirror image thereof;

FIG. 3 is a top plan view thereof;

FIG. 4 is a back elevational view thereof; and,

FIG. 5 is an isometric view of a second embodiment of the seat of my design which differs from the first embodiment only by the addition of another seating section.

1 Claim, 5 Drawing Sheets
